UNITED STATES PATENT OFFICE.

FREDERIC THUMAN, OF LONDON, ENGLAND.

GAS-PRODUCER.

1,398,609.

Specification of Letters Patent. Patented Nov. 29, 1921.

Application filed June 13, 1917. Serial No. 174,482.

To all whom it may concern:

Be it known that I, FREDERIC THUMAN, a citizen of the United States, and residing in London, England, have invented certain new 5 and useful Improvements in Gas-Producers, of which the following is a specification.

This invention relates to gas producers, and especially to water-gas producers, of the kind in which the ashes and clinker are 10 mechanically removed from the base of the producer by the well known means of a rotating base-plate upon which is mounted a grate that projects into the fuel bed and serves as an ash crusher. In such gas producers the ashes are generally raked from 15 off the base-plate or scooped out of the ash pan by a fixed or traveling rake or scoop.

In gas producers of this kind serious damage often arises from the overheating of the 20 grate, usually caused by allowing the hot zone of combustion to descend to the level of the grate, and it has been proposed to cool some such grates by water circulation, water inlet and outlet pipes being provided. This 25 danger from overheating is particularly liable to occur in water-gas generators equipped with rotating grates of the above description, owing to the high temperature at which the process makes it necessary to 30 maintain the fuel bed.

Now according to this invention a rotating grate, which serves as an ash crusher and also as an air and steam twyer, is provided with water inlet and outlet pipes 35 carried by the grate and coaxial therewith where they are coupled to inlet and outlet mains, the said pipes being connected to passages through which the water circulates and cools the grate or such part of it as are 40 liable to become overheated, so that the risk of damage is reduced and the temperature of the grate kept below that at which clinker is liable to form on it.

In the accompanying drawings, Figures 45 1 and 2 show respectively in plan and sectional elevation, the lower portion of a water-gas generator constructed according to this invention.

50 *a* is a cylindrical firebrick-lined fuel chamber, with a water-cooled lining *b*, at the lower section which is usual practice. This chamber is extended below the grate to form the hopper-shaped ash chamber *c*, with discharge door *d*.

55 The annular iron base-plate *e* is supported upon the wheels *f* and is rotated by means

of spur gearing *g*, and shaft *h*, which passes through the side of the ash chamber by the packed gland *i* and is driven in any suitable manner.

Upon the base-plate is mounted the grate which is formed with water-circulating channels *k*, and with openings *l* for the distribution of air and steam to the fire. Depending centrally from the upper part of the grate is a straight pipe *m*, that is also connected to the hollow cylindrical portion of the grate by a branch *m*¹, and surrounding the pipe *m* and attached thereto just below the grate is a pipe *n* which is connected to the two sections of the grate by a branch *n*¹ and extends through a stuffing box *o* that is fixed to the wall of the ash chamber and has its gland *o*¹ formed as a junction box with two compartments, the pipe *n* terminating in the upper one and the pipe *m* extending into the lower compartment.

The cooling-water is brought under pressure through an inlet main *q* into the lower compartment and passes thence through the pipe *m* rotating with the grate into the passages *k* while the effluent water is taken from the passages *k* of the grate by the pipe *n*, which incloses the pipe *m* and passes into the upper compartment of the gland or junction box *o*¹ and thence through an outlet main *r*, the discharge end of which is above the level of the grate. The pipe *n* is protected from contact with the hot ash in the chamber *c* by a tubular extension of the stuffing box *o*.

The ash rake *s* is adjustable from the exterior of the producer. The ash falling into the hopper *c* is periodically removed by the attendant.

The air blast to the generator is supplied through the valve controlled inlet *t*, and the steam by the pipe *u* and sprayer *v*.

Having now particularly described and ascertained the nature of my said invention and in what manner the same is to be performed, I declare that what I claim is:

1. In a gas generator the combination of a 105 rotary grate provided with an ash crusher and a twyer, closed water circulating passages arranged in series and provided in the grate in step wise arrangement and having a water inlet and a water outlet, water inlet and outlet mains, and water inlet and outlet 110 pipes connected with the water inlet and outlet of the passages and carried by the

grate and coupled with the mains co-axially of the grate, substantially as described.

2. The combination in a gas generator of a closed hopper-like generator, a rotary grate 5 provided with an ash crusher and a twyer, closed water circulating passages arranged in series and in step wise arrangement and provided in the grate and having a water inlet and a water outlet, water inlet and

10 outlet mains outside of the generator, water

inlet and outlet pipes connected with the inlet and outlet of the passages and with said mains and carried co-axially of the grate and extending through the wall of the generator, and a tubular covering arranged 15 through the wall of the generator for protecting the pipes from contact with hot ashes, substantially as described.

FREDERIC THUMAN.
